(57) **CLAIM**

We claim the ornamental design for a writing instrument, as shown and described.

DESCRIPTION

FIG. 1 is a top perspective view of a first embodiment of a writing instrument showing our new design;

FIG. 2 is a front view of the writing instrument of FIG. 1;

FIG. 3 is a back view of the writing instrument of FIG. 1;

FIG. 4 is a left side view of the writing instrument of FIG. 1,

the right side view being a mirror image of the left side view;

FIG. 5 is an enlarged top view of the writing instrument of FIG. 1; and

FIG. 6 is an enlarged bottom view of the writing instrument of FIG. 1.

FIG. 7 is a top perspective view of a second embodiment of a writing instrument showing our new design, the difference from the first embodiment being that the grip of the writing instrument has only a single surface texture;

FIG. 8 is a front view of the writing instrument of FIG. 7;

FIG. 9 is a back view of the writing instrument of FIG. 7;

FIG. 10 is a left side view of the writing instrument of FIG. 7,

the right side view being a mirror image of the left side view;

FIG. 11 is an enlarged top view of the writing instrument of FIG. 7; and,

FIG. 12 is an enlarged bottom view of the writing instrument of FIG. 7.

The broken lines showing the clip, upper barrel, and writing tip in FIGS. 1-12 are included for the purpose of showing portions of the writing instrument that form no part of the claimed design.
